UNITED STATES PATENT OFFICE.

FRANKLIN L. ROGERS, OF NEW YORK, N. Y.

TIMBER-CLAMPING DEVICE.

Application filed July 19, 1922. Serial No. 576,137.

to all whom it may concern:

Be it known that I, FRANKLIN L. ROGERS, a citizen of the United States, residing at New York, in the county of New York and 5 State of New York, have invented certain new and useful Improvements in Timber-Clamping Devices, of which the following is a specification.

The present invention relates to devices 10 for clamping timber, such as uprights, balks, and beams, together; and more particularly to devices for clamping uprights together in the construction of scaffolding and similar structures. An object of the invention is to 15 provide a device for such purposes which may be effectively locked in position, which will be of the simplest possible construction, which will be cheap to manufacture, which may be readily attached and detached, and 20 which will be safe and reliable in operation. Other and further objects and features of the invention will appear hereinafter in the specification and be pointed out in the annexed claims.

25 I will now describe the invention with reference to the accompanying drawings which illustrate a preferred embodiment thereof. In these drawings like reference numerals in the several figures designate like parts.

30 Fig. 1 is a side elevation showing the clamping device applied to two uprights, with the parts of the device in the position they are caused to assume before being forced into locking position;

35 Fig. 2 is a similar view showing the parts after they have been forced into locking position;

Fig. 3 is an end view looking in the direction of the arrow (Fig. 2);

40 Fig. 4 is a perspective view of the U-shaped member;

Fig. 5 is a perspective view of the locking plate;

45 Fig. 6 is an end elevation of the locking plate; and

Fig. 7 is a horizontal section through the lines 7—7 of Fig. 2.

Referring more particularly to said drawings, the reference numeral 10 designates a 50 U-shaped member preferably formed of iron or some other suitable metal. The arms of this member, as shown, lie in a plane; and at the ends are bent away to one side of the plane to form the two hooks 11. When it is 55 desired to clamp timber together, such as for example, the two uprights 12 and 13, the

U-shaped member is placed in a position embracing the same as shown in Fig. 1. Along the upper interior edge of the yoke of the member 10 are preferably placed notches, as 60 indicated at 14 in Fig. 4, or teeth or ridges, in order to provide a good gripping or biting edge to engage the timber. As will be seen later on, this upper interior edge is the one which bites or cuts into the timber when 65 the clamp is forced into locking position.

After the member 10 is placed in a position substantially as shown in Fig. 1, a locking plate 15 is fitted into position to cooperate with said member to securely clamp 70 the timber. This locking plate 15, as will be clearly seen from Figs. 5 and 6, consists in its preferred form of a main or intermediate portion arranged in a plane and provided with laterally extending portions 16 75 and 17 arranged in a plane parallel thereto. The opposite sides or edges 20 and 21 of plate 15 are adapted to act as timber engaging edges, while the corresponding opposite sides 18, 19 and 22, 23 of the laterally extending portions are adapted to act as fulcrum edges in the hooks 11; so that a reversible locking plate is thus secured.

The sizes of the member 10 and the plate 15 are so proportioned with relation to the 85 size of the timber to be clamped, that the radial distance from the fulcrum points 11 to the tip of the active timber engaging edge of the intermediate portion of plate 15 is slightly greater than the shortest distance from the same points to the timber. This distance is made just enough greater to 90 make it necessary to force the timber engaging edge into the timber a sufficient distance to obtain a good bite or grip thereon when the device is moved into the locking position 95 shown in Fig. 2.

In order that a single clamp may be used for more than one size of timber, the edge 21 of plate 15 is preferably extended beyond 100 the adjacent fulcrum edges 18 and 19 as shown in Fig. 5. It will be apparent that with such a construction when the plate 15 is reversed from the position shown in Figs. 1 and 2, so that edges 22 and 23 fulcrum in 105 hooks 11, that the distance from the fulcrum point to the timber engaging edge (in this case edge 21) will be greater than in the former case by the amount of the extension, so that the clamp may then be 110 used on smaller sized timber.

After the members 10 and 15 are ar-

ranged in the position shown in Fig. 1, the clamp is locked by forcing the plate 15 about its fulcrum into the position shown in Fig. 2 against the compressional resistance 5 of the timber which is encountered due to the relative proportions referred to in the two preceding paragraphs. When in locked position, it will be noted that the laterally extending portions 16 and 17 lie along the 10 arms of the member 10, on one side of the plane of the arms; but that the timber engaging edge 20, because of its being offset or beyond the plane of said portions, has passed through the plane which includes the 15 fulcrums at 11 and the upper interior edge 24 of the yoke of member 10, and thereby effects a toggle lock. In operation, as the plate 15 moves about fulcrum 11, from the position shown in Fig. 1, toward the position shown 20 in Fig. 2, the member 10 pivots on the interior surface of yoke 24 and moves downward so that its lower surface first passes by edge 20 and then moves into contact with laterally extending portions 17 and 18. The 25 turning of the plate 15 about fulcrum 11 may be effected in any suitable manner; for example, it is generally effected manually by means of a lever provided with a slot in one end adapted to be fitted over the intermediate portion of the plate.

It will be obvious that minor modifications may be made in the design of the cooperating locking plate without departing from the spirit of my invention. It is not 35 essential, for example, that the intermediate main portion of the locking plate be arranged in a plane if the timber engaging edges of the plate be offset from or out of the plane of the laterally extending portions 40 so that when the latter lie along the arms of the U-shaped member the active timber engaging edge is advanced and forms a toggle lock.

Claims.

- 45 1. A toggle-locking timber-clamping device, comprising in combination, a U-shaped member adapted to embrace the timber and having the ends of its arms extending beyond the timber and formed into hooks, 50 a cooperating locking plate having laterally extending portions arranged in a common plane and provided with edges on opposite sides thereof adapted to fulcrum in said hooks, and timber engaging edges on corresponding opposite sides of the intermediate main portion and offset from the plane of the laterally extending portions.
- 55 2. A toggle-locking timber-clamping device, comprising in combination, a U-shaped member adapted to embrace the timber and having the ends of its arms extending beyond the timber and formed into hooks, a 60 cooperating locking plate having laterally extending portions arranged in a common plane and provided with edges on opposite

sides thereof adapted to fulcrum in said hooks, and timber engaging edges on corresponding opposite sides of the intermediate main portion and offset from the plane of the laterally extending portions, one of 70 said timber engaging edges projecting out beyond the adjacent fulcruming edge.

3. A toggle-locking timber-clamping device, comprising in combination, a U-shaped member adapted to embrace the timber and 75 having the ends of its arms extending beyond the timber and formed into hooks, a cooperating locking plate having laterally extending portions arranged in a common plane and provided with edges on opposite sides thereof adapted to fulcrum in said hooks, and timber engaging edges on corresponding opposite sides of the intermediate main portion and offset from the plane of the laterally extending portions, the timber 80 engaging edges being so disposed that the distance from one fulcruming edge of the laterally extending portions to the oppositely disposed timber engaging edge of the intermediate main portion is different from 85 the distance from the other fulcruming edge to its oppositely disposed timber engaging edge.

4. In a toggle-locking timber-clamping device of the character described, a locking plate having laterally extending portions arranged in a common plane, and timber 95 engaging edges on opposite sides of the intermediate main portion and offset from the plane of the laterally extending portions.

5. In a toggle-locking timber-clamping device of the character described, a locking plate having laterally extending portions arranged in a common plane and provided 105 with a fulcruming edge, and an intermediate main portion arranged in a plane parallel thereto and provided with a timber engaging edge.

6. In a toggle-locking timber-clamping 110 device of the character described, a locking plate having laterally extending portions lying in a common plane and provided with oppositely arranged fulcrunning edges, and an intermediate main portion having corresponding oppositely arranged timber 115 engaging edges which edges are offset from the plane of said laterally extending portions.

7. In a toggle-locking timber-clamping 120 device of the character described, a locking plate having laterally extending portions arranged in a common plane and provided with fulcruming edges on opposite sides, and timber engaging edges on corresponding opposite sides of the intermediate main portion and offset from the plane of the laterally extending portions, one of said timber engaging edges projecting out beyond the adjacent fulcruming edge.

8. In a toggle-locking timber-clamping device of the character described, a locking plate having laterally extending portions arranged in a common plane and provided with fulcruming edges on opposite sides, and timber engaging edges on corresponding opposite sides of the intermediate main portion and offset from the plane of the laterally extending portions, the timber en- gaging edges being so disposed that the dis- 10 tance from one fulcruming edge of the laterally extending portions to the oppo- sitely disposed timber engaging edge of the intermediate main portion is different from the distance from the other fulcruming 15 edge to its oppositely disposed timber en- gaging edge.

FRANKLIN L. ROGERS.
